DRILL BIT

William R. Wade, Marysville, Mont.

Application July 20, 1948, Serial No. 39,752

1 Claim. (Cl. 255—64)

1

My invention relates to improvements in a drill bit.

In operation a bending force is exerted upon the drill bit and drill rod each time a blow is delivered on the rod. The bottom of a drill hole is uneven. At each blow of the hammer one or more corners of the bit will be on a hump. The blow causes a bending strain at the connection of the bit to the drill rod. A principal purpose of my invention is to provide a novel bit and a novel means to connect it to the drill rod, cooperating to reduce breakage of the drill rod.

It is also a purpose of my invention to provide a novel drill bit with hardened inserts and with water holes, so constructed and arranged as to eliminate plugging of the water inlets by movement of the inserts and to reduce the possibility of movement of the inserts.

The nature and advantages of my invention, together with other and more specific objects thereof, will appear more fully from the following description and the accompanying drawings of a preferred form thereof.

In the drawings:

Figure 1 is a longitudinal sectional view through a drill bit embodying my invention;

Figure 2 is a fragmentary view in side elevation of the lower portion of the bit;

Figure 3 is a bottom plan view of the bit;

Figure 4 is a side view of a so-called bull bit utilizing a simple hardened insert;

Figure 5 is a sectional view taken on the line 5—5 of Figure 3; and

Figure 6 is a bottom plan view of the bit shown in Figure 4.

Referring now to the drawings, my improved drill bit is illustrated generally by the numeral 10. The drill rod 11 and the bit 10 are connected by threading the rod into the bit. Tapered threads 12 on the bit and matching tapered threads 13 on the rod serve to make this connection. It will be noted that the threads are rounded at the peak to avoid sharp grooves in the drill rod and bit as sharp bottomed grooves promote breakage. The body of the drill bit is long enough to provide a cylindrical socket 14 below the thread in which a cylindrical tip 15 of the rod is seated. The bit 10 also has a collar 16, which extends upwardly on the drill rod for a substantial distance above the threads 13. The drill rod has a central water hole 17 that is in communication with a passage 18 in the bit. The passage 18 extends downwardly into the bit below the socket 14 of the device to provide two diverging passages 19 and 20 that open close to the cutting face of the bit.

The cutting face of the bit body, as illustrated in Figures 1, 2, 3 and 5, has four radially projecting portions 21, 22, 23 and 24. Undercut grooves 25 are provided in the several portions

2

21-24. The grooves meet at the axial center of the drill bit and the faces of the portions 21, 22, 23 and 24 are tapered as illustrated at 26 and 27 at an angle of about 45 degrees to a plane perpendicular to the axis of the bit. The undercut grooves 25 receive hardened inserts 28, 29 and 30. The insert 28 extends all the way across the face of the drill bit as illustrated by Figure 1, while the inserts 29 and 30 are beveled at their inner ends to set flat against the tapered side faces of the insert 28.

In the construction shown in Figures 4 and 6, which illustrate the bull bit, the interior construction is precisely the same as in the construction shown in Figures 1, 2, 3 and 5, however, the bull bit shown in Figures 4 and 6 utilizes a single insert 31 and is beveled at 32 and 33.

According to my invention, the body of the present bit is somewhat longer than the bits now customarily used. The guide collar 16 serves to take the wobble from the bit which is due to the fact that the cutting edges of the bit rarely rests on a plane surface. The bottom of a drill hole is not smooth. At each blow of the air drill, one or more portions of the hardened insert will rest on a hump. The blow transmitted through the drill rod causes a bending action at the connection between the bit and the drill rod. The guide collar 16, which fits closely on the rod 11, transfers this bending strain up the drill rod to a point above where the rod is weakened by a thread. This reduces breakage of the drill rod.

The bottom of the drill rod transmits the drilling blows to the center of the bit. There is ample stock in the bit below the socket 14 to absorb this shock. The provision of the socket 14 and the extension 15 on the rod aids in preventing damage to the threads 12 and 13. The additional length of the bit also serves to steady it in the hole and permits less torsional strain on the drill rod. The guide collar also helps to keep the hole in line and reduces bending in broken rock or seamy rock.

By my construction of the undercut grooves in the face of the drill and the tapering of the sides of the hard inserts 28, 29, 30 and 31, I am able to retain the inserts without any welding or brazing. Brazing is added generally to prevent the insert from being forced out sideways if one end is broken off. The steel of the bit, because it is softer than the insert, is constantly peaned tighter to the insert by the reaction of the steel bit to striking the cuttings as the cutting edge of the hard insert is penetrating the rock.

It will be noted that the bit has no center hole for water, instead it has the two side holes 19 and 20 near the end of the bit. This construction permits the use of one solid unbroken insert 28, or 31 across the face of the bit. This

eliminates the weakness introduced by a center water hole and the two separate inserts against the bit. In drilling, great side pressure develops on the ends of the inserts. This pressure tries to narrow the bit and to reduce its gauge. In those bits where two inserts are used on each cutting edge across the bit, some sort of washer or spacer must be used in the center to maintain the water outlet. The end pressure on the inserts frequently forces the two separate inserts together and closes the water hole. With the two tapered outlets 19 and 20, this weakness is avoided. The angle of the inlets is such that the inlets are not easily plugged by drill cuttings if the rock happens to be soft. The water is forced obliquely to the face of the hole and, because of the rotation of the bit in drilling, a swirling action is maintained by the water. This thoroughly mixes the water with the cuttings and reduces the dust hazard. Also it helps to remove the drill cuttings.

The outer ends of the inserts do more of the work in drilling. The inclined water holes give the outer corners of the inserts the most effective cooling and thus prolong the drilling life of the inserts. The long drill body with the stiffening afforded by the guide collar, also reduces the vibration of the drill body and this in itself aids in keeping the drill cool.

It is believed that the nature and advantages of my invention will be apparent from the foregoing description. Having thus described my invention, I claim:

In combination, a drill rod having a bit receiving end composed of a length of the full diameter of the rod and a tapered portion extended from the length of full diameter, said tapered portion being provided with screw threads, and a drill bit having an elongated guide collar fitting closely on the portion of full diameter of the rod for a substantial distance above the screw

threads thereof, said drill bit having a tapered, rod holding portion extending from the guide collar downward and provided with interior screw threads matching those on the rod, the drill bit having a reduced cylindrical socket below the threads and the rod having a reduced cylindrical extension in said socket and bearing on the bottom thereof, the drill rod having a central water passage and the drill bit having a central water passage in communication therewith, the passage in the drill bit being branched below the rod into smaller downwardly diverging passages, the drill bit having a transverse under cut groove across its working face and a hardened insert in said groove extending full width of the drill face, the diverging passages opening on the working face of the drill bit on opposite sides of said insert.

WILLIAM R. WADE.
